UNITED STATES PATENT OFFICE

THEODORE L. SMITH, OF CONCORD, MASSACHUSETTS, ASSIGNOR TO GILLETTE SAFETY RAZOR COMPANY, OF BOSTON, MASSACHUSETTS, A CORPORATION OF DELAWARE

SAFETY RAZOR

Application filed November 18, 1930. Serial No. 496,445.

This invention relates to improvements in safety razors and blades and one object of the invention is to provide an improved blade which can be used in a plurality of different style razors and which, when used in my improved razor herein disclosed, will have a portion or portions thereof so upset as to permanently mark the blade as having been used.

10 My invention more particularly relates to improvements in a razor and blade of the well-known double-edged Gillette type wherein the blade is provided with three centrally located stud-receiving holes. In the 15 new blade of my invention, I retain the central hole as in the old blade but I considerably enlarge the two outer holes to fit two relatively large and cooperating studs provided on my new razor. I furthermore provide 20 vide tabs extending inwardly from the margin of one or both of the larger blade holes to a point corresponding to the circumference of the smaller stud holes heretofore provided in such blades. When this new blade is assembled 25 in the old style razor, these tabs, in conjunction with the center stud hole of the blade, will serve to accurately locate the blade in shaving position on the razor studs.

My invention furthermore comprises a new 30 and improved razor having a pair of relatively large blade-locating studs to fit the said larger stud-receiving holes in my new blade. The outer portions of these studs which are 35 in position to engage the above-mentioned tabs on the blade are of smaller proportions whereby, when the blade is initially placed on the studs, they engage these tabs and locate the blade in alignment with the cap. Intermediate these portions and the main body 40 of the studs are shoulders which are adapted to engage and upset or break off these tabs when the razor parts are clamped to shaving position, thus marking the blade as having been used. Such a new safety razor blade for 45 the double function defined and a new razor cooperating therewith to perform the blade-marking function comprises important features of my invention.

In the accompanying drawings I have 50 shown certain specific embodiments of my in-

vention but it will be understood that the invention can be otherwise embodied and that the drawings are not to be construed as defining or limiting the scope of the invention, the claims appended hereto being relied upon 55 for that purpose.

Referring to the figures of the drawings, Fig. 1 is a perspective view of one form of my new razor;

Fig. 2 is a longitudinal sectional view 60 therethrough, a portion of the handle being broken away;

Fig. 3 is a plan view of my new blade positioned on the razor cap;

Fig. 4 is a sectional view through the assembled cap, blade and guard taken on line 65 4-4 of Fig. 3;

Fig. 5 is a perspective view of the blade shown in Figs. 3 and 4;

Fig. 6 is a perspective view of the cap 70 shown in Figs. 1 to 4;

Figs. 7 and 8 are perspective views of two other forms of caps which may be used; and

Figs. 9 and 10 illustrate two modifications 75 in the blade.

As stated above, my invention has two main objects, namely to provide a new and improved safety razor blade which can be used in a plurality of different style razors and to provide a blade and razor construction wherein the blade, when clamped into shaving position in the razor, is so deformed or broken without in any manner impairing the utility of the blade as to permanently mark the same as having been used. It is 80 well known that old safety razor blades are collected, resharpened, and sold to the public as new blades. This fraudulent practice is detrimental to both the public and blade manufacturer and one object of my invention is to provide a new safety razor blade which will remedy this situation. My invention as illustrated in the accompanying drawings will now be described.

The razor illustrated comprises a cap 10, a guard 12, a blade 14 between the cap and guard, and a handle 16. The handle has a knurled tubular portion 18 threaded at its inner end to a stud 20 projecting from the cap and tightening of this portion is effective to 100

clamp the blade between the cap and guard. Also projecting from the inner face of the cap are two blade locating studs 22, each comprising a relatively large base portion 24, a reduced outer portion, and an intermediate beveled or shouldered portion. The guard 12 has two corresponding holes for receiving the outer reduced ends of the studs and larger countersunk recesses 28 about the holes for receiving the larger base portions of the studs. The engagement of the reduced portions of the studs within the holes of the guard in conjunction with the engagement of the stud 20 within a hole in the guard serves to accurately locate the guard on the cap.

The blade 14, shown in Figs. 3, 4 and 5, is centrally perforated at 30 and also perforated at 32 in the same locations as is the well-known Gillette safety razor blade of this type, these perforations 32, however, being somewhat larger than have been the usual and corresponding perforations in these blades. It will be noted that a relatively small tab 34 extends partially into each of these holes and each of these tabs is of such length that its inner end is located in what would have been the margin of the hole had it been punched to the usual stud receiving size. This is illustrated by the dotted lines in Fig. 5 which show the usual stud receiving perforations which have heretofore been made in this type of blade.

The outer reduced ends of the studs 22 are preferably of a size corresponding to the correspondingly located studs provided on the well-known Gillette razor of this type. When the blade is placed on the cap, as shown in Fig. 3, the engagement of the stud 20 in the hole 30 locates the blade longitudinally of the cap and when the studs 22 enter the holes 32 the ends of the tabs 34 engage the outer reduced portions of the studs and thereby locate the blade transversely. A five-point contact location of the blade is thereby produced, as is indicated by the arrows in Fig. 3. The guard is located by its engagement with the cap stud and tightening of the threaded sleeve 18 clamps the blade between the cap and guard. The marking of the blade to indicate its used condition is performed at this time and this operation is illustrated in Fig. 4.

The holes 32 in the blade and the corresponding recesses 28 in the guard are of a size to fit and receive the base portions 24 of the cap studs. Clamping the blade between the cap and guard draws the studs 24 into the holes 32 and recesses 28 and bends or upsets the tabs 34, as shown in Fig. 4. The construction is preferably such as to entirely break the tabs from the blade but, if desired, the tab may be bent only out of the plane of the blade. These results depend upon such conditions as the temper of the tabs 34 and the

size of the stud portions 24 relatively to the holes 32 and recesses 28.

As above stated, the reduced end portions of the studs 22, as shown in Fig. 3, are of a size corresponding to the correspondingly located studs provided on the well-known Gillette razor of this type. It will, therefore, be clear that this blade will fit such razor in the same manner as it fits these stud portions and may be used interchangeably in both these razors.

While I have above described a specific construction for both razor and blade, it will be clear that it has been only for the purpose of defining and illustrating my invention and that the invention may be considerably modified without departing from the spirit thereof. For example, in Figs. 7 and 8 I have illustrated two razor caps 40 and 50 having other forms of studs which serve the same functions as the studs 22. The studs 42 on the cap 40 are cylindrical and of a size corresponding to the base portion 24 of stud 22. The opposite sides of these studs are, however, grooved at 44 to receive the tabs 34. These grooves are deepest at their outer ends and the bottoms thereof gradually flare outwardly toward the base of the studs. When placing a blade 14 on this cap, the tabs 34 enter the grooves 44 which thereupon automatically center the blade transversely, the distance between each two oppositely located grooves at their outer ends preferably being equal to the diameter of the blade locating studs on the said Gillette razor.

The studs 52 on the cap 50 have their outer ends wedge shaped at 54 whereby to engage the tabs 34 and automatically center the blade placed thereon. The guard which receives the caps 40 or 50 will have through stud receiving holes of a size corresponding to the studs and when the blade is clamped between the guard and cap the tabs will be upset or broken off, as will be apparent.

The blade may also be considerably modified within the scope of my invention and in Figs. 9 and 10 I have illustrated two such modifications. From the above description it is clear that when the blade is located on the central stud 20 it is only necessary to then locate the blade transversely. This is done in Fig. 3 by providing two tabs 34 within the two blade apertures 32. This locating may also be done by placing the two tabs in one of the apertures, as in Fig. 9. This blade 60 has a central perforation 62, a large stud receiving hole 64 and a like stud receiving hole 66 with two oppositely located tabs 68 extending thereinto. These two tabs will serve the purpose of locating the blade transversely in the same manner described in reference to the blade 14. The blade 60 may also have a pair of tabs in each of the large stud receiving holes, if desired. Such a blade 70 is shown in Fig. 10.

Having thus described my invention, what I claim as new and desire to secure by Letters Patent is:

1. A safety razor comprising a cap member, a guard member, studs on one of the members for engaging in locating holes in the other member, the members being adapted to hold a blade therebetween with the studs engaging within holes in the blade, one of the studs being reduced toward its free end whereby a shoulder is formed thereon and said reduced portion being adapted to locate the blade by engaging a tab extending into the stud receiving blade aperture, and means for clamping the members together, the said shoulder being adapted to upset the tab when the blade is clamped into shaving position.

2. A safety razor comprising a cap member, a guard member, studs on one of the members for engaging in locating holes in the other member, the members being adapted to hold a blade therebetween with the studs engaging within holes in the blade, opposite sides of one of the studs being reduced towards its free end whereby shoulders are formed on such sides and said reduced portion being adapted to locate the

blade apertures, and means for clamping the members together, the said shoulders being adapted to upset the tabs when the blade is clamped into shaving position.

5. A safety razor comprising a cap, three blade locating studs centrally disposed in line longitudinally of and projecting outwardly therefrom, the outer studs being tapered toward their free ends on opposite sides of the longitudinal center line through the cap in a manner forming oppositely disposed shoulders on the studs adjacent to their base portions, a cooperating guard provided with three holes for receiving the studs, the studs being adapted to receive and locate a blade provided with a central stud receiving hole and two outer holes each of the latter having a tab on and extending transversely of the blade less than a radius length thereinto, and a handle threaded to the central stud for drawing the cap and guard together, the said tapered stud portions being adapted to locate the blade by engaging the tabs and the shoulders being adapted to engage and upset the tabs when the handle clamps the blade between the cap and guard.

6. A safety razor comprising a cap having blade locating studs projecting therefrom
